APPARATUS FOR SUPPRESSING INTERFERENCE IN RADIO SELECTOR SYSTEMS

Application filed March 6, 1928. Serial No. 259,454.

This invention relates to radio receiving apparatus, and relates more particularly to a system for selecting electrical oscillations of a given frequency band from oscillations differing therefrom in frequency; and has special reference to the provision of means for suppressing oscillations differing in frequency from the frequency of the selected band.

The prime object of the present invention is to improve the efficiency of a selector system for radio receiving apparatus and to sharpen the selectivity characteristic of such a system. More specifically, it is the object of the invention to increase the energy at the desired or selected frequency available at the output of the selector system and to minimize the energy of the interfering or undesired frequencies which are transmitted through the selector system especially in frequency bands several percent removed from the desired frequency band.

It is well known that sharply tuned circuits in cascade, moderately coupled together, will transmit a narrow band of frequencies and cut off frequencies higher and lower than that to which the circuits are tuned. It is also well known that by increasing the number of circuits in cascade, the amplitude of the interfering frequencies may be reduced in substantially geometric ratio, especially where these interfering frequencies are different from the resonant frequency by an amount sufficient to create reactance components in the tuned circuits from 5 to 10 times the circuit resistance. It is also known that as the number of cascaded circuits is increased, the energy available at the output of the selector system is decreased.

I have found in the operation of these selector systems that an increase in the number of tuned or resonant circuits beyond four produces relatively small selectivity gains and relatively high energy losses. By means of the present invention, I have found that I am enabled to obtain a further increase of selectivity in the system beyond that which can normally be secured with four tuned circuits without the addition of another

tuned circuit and with an increase in the amount of energy available at the output beyond that which can be secured by the four normally tuned circuits alone.

To the accomplishment of the foregoing and such other objects as will hereinafter appear, my invention consists in the elements and their relation one to the other as more particularly described hereinafter and sought to be defined in the claims; reference being had to the accompanying drawing which shows the preferred embodiment of my invention, and in which:

Fig. 1 is a wiring diagrammatic view showing the application of my invention to a selector system for a radio receiving apparatus.

Figs. 2 to 4 are graphical representations explanatory of the operation of the system of my invention, and

Fig. 5 is a wiring diagrammatic view showing the preferred manner of arranging the circuit.

Referring now more in detail to the drawing, and having reference first to Fig. 1 thereof, I show my invention applied to a selector system having a chain of circuits such as 1 to 4 inclusive coupled together in cascade, the individual circuits being adjustable so as to make the same resonant to the band of frequency of the oscillations desired to be selected. The individual circuits of the chain embody capacitive and inductive components which comprise the capacitive circuit tuning elements C1, C2, C3 and C4 in the form of variable condensers and the inductance elements L1, L2, L3 and L4, the inductive components of the various circuits also including the coupled coils forming the coupling transformers M1, M2 and M3, all of the couplings between adjacent resonant circuits being in the same sense.

I have discovered that the currents of oscillations differing from the selected band of frequencies may be opposed or suppressed and that the currents of the resonant oscillations, that is the frequency band desired to be selected, may be aided by the provision of an auxiliary coupling between non-adjacent circuits of the selector chain. More

specifically, I have found that with a given number of circuits in the selector chain and with a suitable coupling between certain non-adjacent circuits thereof, the interfering frequencies on both sides of the desired frequency band may be substantially equally suppressed, thus increasing the selectivity of the system, and that the currents of the resonant frequencies may be augmented, thus increasing the energy at the output of the selector system.

The invention is especially applicable to a chain of circuits coupled together by fixed couplings and preferably at optimum values. The coupling transformers M₁, M₂ and M₃ are therefore fixed and arranged preferably after the manner shown in Fig. 5 of the drawing, as will be explained further hereinafter. To carry out the intended object with greatest efficacy, as will be explained further in connection with Figs. 2 and 4 of the drawing, the number of circuits in the chain should be even and at least four in number, as shown in Fig. 1 of the drawing. The circuits are also preferably arranged so that there is no energy transfer between non-adjacent circuits except through the couplings therebetween, all as disclosed and claimed in my copending application Ser. No. 243,790, filed Dec. 31, 1927, to Selector system for radio receiving apparatus. The energy may be supplied to and taken from the circuits in the manner disclosed in that application, Fig. 1 therein corresponding to Fig. 1 in the present application, or simply through conductors connected at either side of condensers C₁ and C₄, as shown in the drawing.

In applying my invention to a four-circuit arrangement such as shown in Fig. 1, the auxiliary coupling which I provide is arranged between the first and fourth circuits, the said auxiliary coupling comprising a coil A connected in series with the elements of the first resonant circuit 1, the said coil being coupled to the coil L₄ of the last circuit of the chain, the coupling between A and L₄ being in a sense opposite to the coupling existing between adjacent circuits. The coupling between the auxiliary coil A and the inductance L₄ is adjusted so as to diminish or eliminate the residual interference of undesired frequencies which are removed by several percent from the desired frequencies. By means of this arrangement, interference on both sides of the desired frequency band is eliminated and in equal degrees and the currents of the selected frequencies are augmented.

The new results achieved by the circuit arrangement of my invention may be explained by the following theory, which is submitted merely by way of explanation, but not by way of limitation, this theory

being the one I believe to be explanatory of the results produced.

In the first circuit 1 of the selector chain, there is present, besides the currents of the desired frequencies, considerable current of the interfering or undesired frequencies, the ratio of these currents being determined by the relative strengths of the desired and interfering signals and by the ratio of the resistance of the tuned circuit to its reactance at the undesired frequency. In successive tuned circuits the interfering circuits become relatively much weaker, and where the undesired frequencies are different from the desired frequencies by several percent, the intensity of the undesired currents decreases substantially in geometric progression from circuit to circuit. The percentage difference between desired and undesired frequencies at which this phenomenon takes place is determined by the sharpness of tuning of the individual circuits, assuming the circuits to be coupled at optimum coupling. The condition at which this becomes effective appears to be that the reactance of the tuned circuits at the undesired frequencies, must be the product of the number of circuits in cascade and two or three times the individual circuit resistance. At frequencies closer to resonance than these, the interfering currents in the later circuits of the chain do not diminish and at frequencies very close to resonance they may even be greater than what might be secured with a single tuned circuit alone.

It will be seen therefore, that in the frequency range of which I am speaking there exists in the last of the chain of circuits interfering currents substantially weaker than interfering currents in the first tuned circuit. By coupling the first circuit directly with the fourth I oppose the interfering current in the fourth circuit by some of the field generated by the interfering current in the first circuit. Moreover, the coupling required to produce this opposition produces an aiding relationship between the resonant or desired current in the fourth circuit and the resonant field of the first circuit, so that the amplitude of the resonance currents in the fourth circuit is substantially increased.

This effect can be secured with a chain of three or five circuits coupling the first to the last, but only with a diminution of interference on one side of resonance and an increase of interference on the other side of resonance. A deeper insight into the underlying relationships, explaining the difference in results obtained with even and odd numbers of cascaded circuits can be had by consideration of the vector showings in Figures 2, 3, and 4.

In Fig. 2 of the drawing, I₁ indicates the resonance current in circuit 1. Assuming that circuits 1 and 2 are coupled (in a given

sense) so that the electromotive force introduced into circuit 2 lags behind the current in circuit 1, then I2 will represent the phase of the resonance current in circuit 2 with respect to I1. Circuit 3 being similarly coupled to circuit 2, that is so that the voltage induced in 3 also lags, I3 represents the phase of the resonance currents in circuit 3. Similarly I4 represents the phase of the resonance current in circuit 4. Now, if a coupling be provided between circuits 1 and 4, in the sense opposite or reversed to the couplings between adjacent circuits, that is the coupling being such that the voltage induced 15 leads the current I1, then the voltage and current induced in circuit 4 directly from circuit 1 will be phased as shown by the vector I4A. This being in the same direction as I4 is additive therewith, and explains the 20 increase in resonance current due to the coupling of this invention.

In Figure 3 of the drawing is shown a corresponding set of vectors showing the relationships existing between the interfering currents of frequencies higher than the resonant frequency. Assuming the phase of the interfering current in circuit 1 to be as shown in I1, the interfering current in circuit 2 will be as shown by I2. This is because the voltage induced into circuit 2 lags 25 90° behind the current in circuit 1 and the interfering current in circuit 2 lags substantially 90° behind the induced voltage because circuit 2 presents an inductive reactance to the higher frequency interfering currents. This phase angle is substantially 30 90° because we have postulated that the reactance of the circuit for these interfering frequencies is 8 or more times the circuit 35 resistance. Similarly the interfering currents in circuits 3 and 4 are as shown by I3 and I4. Now the voltage induced into circuit 4 by the direct coupling with circuit 1 will be phased as shown by E4A, since this 40 coupling is arranged to produce voltages leading the currents in circuit 1. Since the interfering current in circuit 4 lags behind the induced voltage the interfering current will be phased as shown by I4A, or oppositely to the interfering current due to the 45 coupling through the intermediate tuned circuits. Then by suitably adjusting the direct coupling between circuits 1 and 4 currents I4 and I4A may be made to substantially oppose each other and so reduce the 50 interfering energy to a minimum.

In Figure 4 are shown the phase relationships for interfering currents of lower frequencies than the desired frequency. Here again assuming that the interfering current in circuit 1 is phased as shown by I1, the interfering current in circuits 2, 3 and 4 will be as shown by I2, I3, I4. These phase relationships exist because now the tuned circuits present capacitive reactance to the in-

terfering frequencies and therefore, the interfering currents in them lead the induced voltages by substantially 90°, thereby compensating for the lagging induced voltage due to the coupling between the adjacent circuits. Similarly E4A represents the leading phase of the voltage induced directly into circuit 4 from the interfering current in circuit 1. The current induced thereby in circuit 4 leads E4A by substantially 90° giving rise to current I4A. This being opposed to I4 tends to minimize the interfering energy.

Further consideration of Figures 2, 3 and 4 will show that a coupling between odd circuits such as, for example, between 1 and 3, would give rise to oppositely phased interference components, which would assist the low frequency interference and diminish the high frequency interference with the couplings arranged as described above. Reversing any one of the couplings would merely serve to change the assisting interference component from low to high frequency.

The additional or auxiliary coupling between the first and fourth circuits may be made fixed at a value indicated by a majority of experience cases found to be desirable or it may be made variable over a moderate range under the control of the receiving set operator so as to be exactly adjustable to meet any special case of residual interference.

In Fig. 5 of the drawing, I show a preferred way of fixedly adjusting the couplings between adjacent circuits with a maximum or optimum degree of coupling. By means of the method shown in Fig. 5 of the drawing, I am enabled to construct in a simple and inexpensive way a selector system in which substantial optimum coupling may be maintained over a wide frequency band without the necessity of making any manual adjustments between the circuits. The individual circuits of the selector chain designated by reference characters similar to that used for Fig. 1 of the drawing are first coupled together and the degree of inductive coupling adjusted so that at the lowest frequency of the band the couplings are slightly less than the optimum value. I then tune to the highest frequency of the band for which the selector is designed and supplement the inductive coupling of each circuit with a capacity coupling designated by the condensers K1, K2 and K3, the supplemental coupling functioning to increase the coupling between adjacent circuits to the higher degree necessary for the optimum coupling at the higher frequencies. Now returning to the lower frequencies, it will be found that this additional capacity coupling produces little change in the degree of coupling and sufficient only to bring the total coupling

up to the optimum value. If the original inductive coupling selected is too strong or too weak, a secondary correction may be desirable.

5 In order to have the capacitive coupling due to the condensers K1, K2 or K3 supplement the inductive coupling, it is necessary that the inductive coupling be in the correct sense. This may be obtained by 10 coupling the coils so that the high potential electrodes of adjacent condensers are at opposite potentials. If the inductive coupling be in the opposite sense, then the capacitive coupling will oppose the magnetic coupling and intensify the departure 15 from the desired optimum coupling over the band of frequencies for which the selector is designed.

Preferably the coils are constructed with 20 Litz wire, and when so constructed the Litz coils generally show a fairly sharp rising resistance characteristic at the higher frequencies. This generally necessitates a stronger coupling between tuned circuits at 25 the higher frequencies in order to maintain optimum coupling over the broadcast band. The theory of coupled circuits shows that at optimum coupling the mutual is related to the circuit resistance by the formula 30 $R=2\pi f M$. If the resistance of the Litz coils increases linearly with the frequency, a constant inductive coupling would be insufficient. It is found in practice, however, that at the higher frequencies the circuit 35 resistances mount more sharply than linearly with the frequency, due in part to unavoidable dielectric losses and in part to the resistance characteristic of the Litz wire. The capacitive coupling due to the condensers K1 to K3 is most strongly effective 40 at these high frequencies.

In the embodiments of the invention described, it is assumed that the couplings M1, M2 and M3 between adjacent circuits are 45 all in the same sense. This is the simplest case to consider; and in such a case the coupling of the coil A is in a sense opposite or reverse to the coupling between any of the adjacent circuits. Where I speak of 50 the "coupling between adjacent circuits of the chain", I mean the resultant adjacent couplings of the chain rather than the sense of coupling between any individual coupling M1, M2 or M3. As heretofore stated, 55 a reversing of any one of the couplings would merely serve to change the assisting interference component from low to high frequency, and therefore such a reversing of any one of the adjacent couplings has 60 no effect on the number of circuits desired for the chain. However, a reversing of any one of the adjacent couplings would affect the sense or direction of the auxiliary coupling. To make this clearer, the sense 65 of couplings may be conventionally de-

scribed as being either positive or negative. If all of the couplings M1 to M3 are considered positive (corresponding to the production of a leading voltage effect) then the sense of the coupling of the coil A 70 would be negative (corresponding to the production of a lagging voltage effect). If, however, any one of the couplings M1 to M3 is negative and the other two positive, then the coupling of the auxiliary coil A is reversed and should be made positive. If, however, any two of the couplings M1 to M3 are made negative, leaving the third coupling positive, then the sense of the coupling coil A becomes and should be negative. In effect the two negative adjacent 80 couplings cancel each other to produce the same result as in the first illustration with all of the adjacent couplings positive. If, however, all of the couplings M1 to M3 are 85 made negative, then the coupling of A is positive; and by comparison with the first-mentioned example it will be seen that with all of the adjacent couplings the same, the general rule applies. As a general rule to 90 be applied to any even number of circuits which would have an odd number of couplings, the sense of the auxiliary coupling is opposite to that of the sense of the odd number of similar couplings. 95

While I prefer to set the couplings experimentally as described, the values of capacitive and inductive couplings to be used for any given case may be calculated from the above considerations applied to a curve 100 showing the circuit resistance characteristic with the frequency.

The use and operation of the improved selector system of my present invention and the many advantages thereof will in the 105 main be fully apparent from the above detailed description thereof. It will be further apparent that while I have shown and described my invention in the preferred form, that many changes and modifications 110 may be made in the structure disclosed without departing from the spirit of the invention, defined in the following claims.

I claim:

1. A system for selecting electrical oscillations of a given frequency band from oscillations differing therefrom in frequency comprising a chain of circuits coupled in cascade and all tuned alike and resonant to the mean frequency of the oscillations to be selected, and means for suppressing the oscillations of frequencies outside the selected band of frequencies, said means comprising a coupling between non-adjacent 115 circuits of the chain. 120

2. A system for selecting electrical oscillations of a given frequency band from oscillations differing therefrom in frequency comprising a chain of circuits coupled in cascade and all tuned alike and resonant 125

to the mean frequency of the oscillations to be selected, and means for suppressing the oscillations of frequencies outside the selected band, said means comprising an auxiliary coupling between non-adjacent circuits of the chain coupled in a sense opposite to the coupling between adjacent circuits of the chain.

3. A system for selecting electrical oscillations of a given frequency band from oscillations differing therefrom in frequency comprising a chain of circuits coupled in cascade and all tuned alike and resonant to the mean frequency of the oscillations to be selected, the couplings between the circuits being fixed and at optimum coupling values, and means for suppressing the oscillations of frequencies outside the selected band, said means comprising an auxiliary coupling between non-adjacent circuits of the chain.

4. A system for selecting electrical oscillations of a given frequency band from oscillations differing therefrom in frequency comprising a chain of at least four circuits resonant to the frequency of the oscillations to be selected and coupled in one sense in cascade, and means for suppressing the oscillations differing in frequency from the selected band, said means comprising an auxiliary coupling between the first and the last circuits of the chain coupled in a sense opposite to the coupling between adjacent circuits of the chain.

5. A system for selecting electrical oscillations of a given frequency band from oscillations differing therefrom in frequency comprising a chain of circuits coupled in cascade and all tuned alike and resonant to the mean frequency of the oscillations to be selected, and a coupling between non-adjacent circuits of the chain so related to the coupled circuits of the chain as to suppress the interfering oscillations of frequencies outside the selected band on both sides of the selected band substantially equally.

6. A system for selecting in geometrical progression electrical oscillations of a given frequency band from oscillations differing therefrom in frequency comprising a chain of circuits coupled in cascade and all tuned alike and resonant to the mean frequency of the oscillations to be selected, the reactance of the resonant circuits to undesired frequencies being the product of the number of circuits and at least twice the resistance of an individual circuit, and a coupling between non-adjacent circuits of the chain related to the coupled circuits of the chain to substantially equally suppress the interfering oscillations on both sides of the frequency band selected.

7. A system for selecting in geometrical

progression electrical oscillations of a given frequency band from oscillations differing therefrom in frequency comprising a chain of four or greater even number of circuits resonant to the frequency of the oscillations to be selected and coupled in cascade, the reactance of the resonant circuits to undesired frequencies being the product of the number of circuits and at least twice the resistance of an individual circuit, and an auxiliary coupling between the first and last circuits of the chain related to the coupled circuits of the chain and adjusted to substantially equally suppress the interfering oscillations on both sides of the frequency band selected.

8. A system for selecting in geometrical progression electrical oscillations of a given frequency band from oscillations differing therefrom in frequency comprising a chain of circuits coupled in cascade and all tuned alike and resonant to the mean frequency of the oscillations to be selected, and means for opposing the currents of oscillations of frequencies outside the selected band and for aiding the currents of the resonant oscillations, said means comprising an auxiliary coupling between selected non-adjacent circuits of the chain.

9. A system for selecting in geometrical progression electrical oscillations of a given frequency band from oscillations differing therefrom in frequency comprising a chain of an even number and at least four circuits resonant to the frequency of the oscillations to be selected and coupled in cascade, the said circuits being fixedly coupled with a maximum coupling, and means for opposing the currents of oscillations differing from the selected band and for aiding the currents of the resonant oscillations, said means comprising an auxiliary coupling between the first and the last circuits of the chain coupled in a sense opposite to the couplings between adjacent circuits of the chain, the reactance of the resonant circuits to undesired frequencies being the product of the number of circuits and at least twice the resistance of an individual circuit.

10. In combination, a pair of resonant circuits each comprising a fixed inductance and a variable tuning condenser arranged in series therewith for tuning said circuits over a predetermined frequency band, said circuits being tuned alike and inductively coupled together and a relatively small capacity coupling insufficient to substantially affect the tuning of the circuits and supplementing the inductive coupling between the circuits, the capacitive and inductive couplings being related to produce optimum coupling over the said predetermined frequency band.

LESTER L. JONES.
